(57) CLAIM

We claim the ornamental design for a placemat with spill collector, as shown and described.

DESCRIPTION

FIG. 1 is a bottom, left, front perspective view of the placemat with spill collector;

FIG. 2 is top side elevation view thereof;

FIG. 3 is a front elevation view thereof;

FIG. 4 is a bottom side elevation view thereof

FIG. 5 is left side elevation view thereof, the right side being mirror image of the side shown; and,

FIG. 6 is a back elevation view thereof.

The broken lines in the drawings are for illustrative purposes only and form no part of the claimed design.
